UNITED STATES PATENT OFFICE.

RUFUS M. EVANS, OF TECUMSEH, KANSAS, ASSIGNOR OF ONE-HALF TO CHARLES SCHWARTZ, OF TOPEKA, KANSAS.

RAIL-BRACE.

1,084,260.

Specification of Letters Patent.

Patented Jan. 13, 1914.

Application filed August 4, 1913. Serial No. 782,755.

To all whom it may concern:

Be it known that I, RUFUS M. EVANS, a citizen of the United States, residing at Tecumseh, in the county of Shawnee and

5 State of Kansas, have invented certain new and useful Improvements in Rail-Braces, of which the following is a specification.

10 My invention is an adjustable brace for railroad rails. Its object is to provide a simple and efficient rail brace that can be easily applied, and which is so adjustable as to be adapted not only to operate as an efficient rail brace but also to bring the rail into an exact line. It comprises essentially 15 a plate adapted to embrace the rail, a lug adapted to be secured to the tie apart from the rail, and a bolt having a threaded engagement with the lug and extending between the plate and the lug; and it also 20 consists of the parts, improvements, and combinations hereinafter set forth and claimed.

25 In the drawings accompanying and forming part of this specification and in the description of the drawings, I have shown my invention in its preferred form, and have shown what I deem to be the best mode of applying the principles thereof; but it is to be understood that I contemplate 30 plate changes in form, proportions, and materials, the transposition of parts, and the substitution of equivalent members, without departing from the spirit of my invention.

35 Figure 1 is a sectional elevation of a rail brace made in accordance with the principles of my invention, with a section of a rail to which it is applied, and a dotted outline of the top of the tie. Fig. 2 is a plan view of the rail brace, with a dotted outline 40 of the tie.

Similar reference characters indicate like parts throughout both views.

45 3 is a rail and 4 is a tie on which the rail is supported.

50 5 is a plate adapted to bear against the side of the web of the rail between the base and the head, its outer face being slightly inclined so as to be thicker at the top than at the bottom, and 7 is a flange of the plate adapted to engage the base of the rail. At each end, the flange is extended in the form of a hook 8 to embrace the under side of the base of the rail.

55 9 is a lug, preferably made integrally

with the base plate 10, which is provided with suitable holes 11, 11 for spiking it to the tie.

12 is a bolt whose outer end 13 is threaded and has threaded engagement with the lug, and whose inner end is angular in cross-section so that it may be turned by applying a wrench thereto. The angular end terminates with a pin 15 which is adapted to enter a hole 16 in the plate 5 to hold 60 the bolt from lateral displacement, the shoulder formed at the junction of the angular portion and the pin bearing against the plate 5 on the inclined face 6. Preferably this incline is at right angles to the line 65 of the bolt which slants downwardly from the rail end so as to form a brace.

70 17 is a lock-nut for locking the bolt in any position.

75 As noted from the drawings, the lug is secured to the tie separately and apart from the rail, thus depending for its permanency of position upon its attachment to the tie. The brace plate 5 is placed against the side of the rail in the position shown, and is long 80 enough so that the hooks at the ends embrace the rail base on opposite sides of the tie. When the lug is spiked down to the tie and the brace plate is properly positioned, the bolt is forced against the brace plate by turning it by applying a wrench to the angular portion. Obviously, it is possible not only to bring the bolt up firmly 85 against the brace plate but also to move the rail if desired. When the bolt is in its 90 proper position, the lock-nut may be screwed down against the face of the lug, thus holding the bolt against turning, and forming a perfectly rigid brace. It is also to be noted that the brace may be easily 95 adjusted from time to time as may be desired, that the contraction and expansion of the rails do not affect it, and that the rail may be removed and replaced without removing the lug from the tie.

100 100 What I claim is:

1. The combination of a flanged plate adapted to embrace the side of the web and the top of the base of a rail and having a hook at each end embracing the underside 105 of the base of the rail, the plate being inclined inwardly toward the web from the top downwardly and having a hole; a lug having an integral plate for securing it to a tie apart from the rail and first-named 110

plate; a bolt extending between the first-named plate and the lug, having threaded engagement with the lug and having a pin at its opposite end which engages in said hole, the portion of the bolt adjacent to the pin end being angular in cross section; and a lock-nut on the bolt bearing against the face of the lug.

2. The combination of a flanged plate 10 adapted to embrace the side of the web and the top of the base of a rail and having a hook at each end embracing the under side of the base of the rail, said plate having a hole; a lug adapted to be fastened to a tie 15 separately and apart from the rail and plate; a bolt, one end of which is threaded and has threaded engagement with the lug, and the other end of which is angular in cross section and terminates with a pin and

shoulder, said pin engaging in said hole 20 and said shoulder bearing against said plate, and a lock-nut on the bolt bearing against said lug.

3. The combination of a plate adapted to embrace the side of a rail, a lug adapted to 25 be fastened to the tie apart from the rail, a bolt having threaded engagement with the lug and bearing against the plate and having an angular portion for the application of a wrench thereto, and a lock-nut on the 30 bolt bearing against the face of the lug.

In testimony whereof I have affixed my signature in presence of two witnesses.

RUFUS M. EVANS.
